UNITED STATES PATENT OFFICE.

JAMESON M. BURROWS AND HENRY F. TRENARY, OF NEWKIRK, OKLAHOMA.

VALVE.

1,272,913.

Specification of Letters Patent. Patented July 16, 1918.

Application filed June 13, 1916. Serial No. 103,523.

To all whom it may concern:

Be it known that we, JAMESON M. BURROWS and HENRY F. TRENARY, citizens of the United States, residing at Newkirk, in the county of Kay and State of Oklahoma, have invented new and useful Improvements in Valves, of which the following is a specification.

This invention relates to a valve which may be used in connection with gas pipes and more particularly to a valve which is operated by the pressure of the gas within the pipes to which the valve is applied.

The primary object of the invention is to provide a valve which when connected with a gas main in advance of the burners will be normally held in open position by the pressure of the gas within the main, but upon the diminution of gas pressure within the pipe the valve will be moved to closed position by gravity and held in such position by a spring controlled latch connected therewith, thus preventing the escape of gas through the burner tips when the pressure again increases in the gas main.

Another object of the invention is to provide a valve of this character having connected therewith a receptacle in which weights may be placed to increase the weight of the valve and cause the same to act in opposition to the gas pressure within the gas main to which the valve is applied, thus adapting the valve for use in either high or low pressure systems.

A further object of the invention is to provide a valve for connection with gas mains which is so constructed that it obviates the necessity of supplying the burner arm connected with the valve with a stop cock for controlling the flow of gas through the arm.

With these and other objects in view, the invention resides in the novel combination and arrangement of parts, which will be hereinafter described and particularly pointed out in the claim.

The preferred embodiment of the invention has been illustrated in the accompanying drawing, although no restriction is necessarily made to the precise details of con-

struction therein shown, as changes, alterations, and modifications, within the scope of the claim may be resorted to when desired.

Like characters of reference denote corresponding parts, throughout the several views in the drawing, in which:

Figure 1 is a side elevation of a valve constructed in accordance with the invention and showing the same applied to a gas main and having connected therewith a burner arm.

Fig. 2 is a view similar to Fig. 1 showing the valve held in open position by the gas pressure within the main.

Fig. 3 is a view similar to Fig. 2 showing the valve in closed position and the gas cut off from the tip on the burner arm.

Fig. 4 is a horizontal section on the line 4—4 of Fig. 2.

Fig. 5 is a horizontal section on the line 5—5 of Fig. 3.

Referring now to the drawing in detail, the numeral 1 designates a valve casing which is cylindrical in shape and interiorly threaded at one end, as at 2, for connection with a gas main 3.

The valve casing 1 is further provided on its outer peripheral face between its ends with an enlargement or boss 4 having formed therein a threaded opening 5 adapted to receive the end of a burner arm 6 having connected therewith a burner tip 7.

The other end of the valve casing 1 is offset, as at 8, to form an annular shoulder 9 and an upstanding and internally threaded annular flange 10, said shoulder forming a seat for a packing ring 11.

A disk or cap 12 has its peripheral surface threaded, as at 13, to engage with the threads on the inner face of the annular flange 10, so that the cap or disk is removably connected with the valve casing 1 and provides a closing cap for the open end of the valve casing.

An extension 14 is provided upon the disk 12 and the said extension has angular faces which may be engaged by a wrench for applying or removing the disk 12. The said extension 14 is provided at one side with an opening 15.

A valve stem 17 which is substantially square in cross section is mounted to slide in the opening 16 and has formed thereon at one end a reduced and threaded extension 18.

Disks 19 and 20 are mounted on the threaded extension 18 and held in spaced relation by a packing disk 21 which is of greater diameter than the disks 19 and 20, 10 said packing being clamped by the disks 19 and 20 through the medium of a nut 22 adjustably mounted on the threaded extension 18, said disks and packing forming a valve head 23 movable longitudinally of the valve 15 casing 1.

The valve stem 17 has formed therein between its ends a notch 24 above which is removably connected with the stem 17 a weight box 25 having a removable cover 26, said 20 box being adapted to receive lead shot, or the like, to increase or decrease the weight of the valve 23.

A latch bar 27 which is passed through the recess 16 has one end pivotally connected 25 with the disk or cap 12 and has its other end formed with an operating handle 28.

A contractile spring 29 has one terminal connected with the latch bar 27 adjacent the operating handle 28 and its other end with 30 a stud 30 on the cap or disk 12, said spring normally tending to hold one side edge of the latch bar against the valve stem 17, so that when the notch 24 in the valve stem has been brought into registration with the 35 latch bar in a manner which will be presently described, the latch bar will be received in said notch to lock the valve against sliding movement within the valve casing 1.

A coil spring 31 encircles the valve stem 40 17 above the disk 19 and has one end thereof arranged to contact with the cap 12 when the valve is in open position, said spring 31 serving as a cushion for the valve and preventing the same from sticking within the 45 casing 1.

When the valve casing 1 has been connected with a gas main and with a burner arm as shown in Fig. 2 in the drawing, the gas 50 pressure within the main will cause the valve to assume the position within the casing shown in Fig. 2 in the drawing provided the latch bar 27 has been disengaged from the notch 24 in the valve stem 17.

When the valve in the casing 1 is in the 55 position shown in Fig. 2 in the drawing, it will be seen that the gas from the main can pass through the burner arm and out through the tip associated therewith, so that the gas may be ignited at the tip for illuminating purposes.

When the valve in the casing 1 is in the 60 position shown in Fig. 2 in the drawing and gas ignited at the burner tip, should the

gas pressure in the main decrease so that the flame at the burner tip would become extinguished the decrease in gas pressure in the main permits the valve to move to the position shown in Fig. 3 in the drawing, thus cutting off communication between the burner tip and the gas main. 65

As the valve head 23 moves downwardly, the notch 24 in the stem 17 is brought into registration with the latch bar 27 which under the influence of the spring 30 is moved within the notch 24 and locks the valve 75 against movement, so that when the pressure in the gas main again increases the gas is prevented from escaping through the burner arm and tip and filling the apartment in which the fixture is located with gas. 70

When the valve has been locked in closed position by the latch bar and the pressure in the gas main again increases it is necessary to manually release the latch bar from the notch 24 in the stem 17 before the gas 85 pressure in the gas main can move the valve to a position in the casing as shown in Fig. 2 in the drawing.

When the gas pressure in the main is normal and it is desired to extinguish the 90 flame at the burner tip, pressure may be exerted on the weight box by means of the finger to move the valve head 23 below the opening 5 in the casing, thus extinguishing the flame at the burner tip and the valve 95 may be locked in this position through the medium of the latch bar 27 thus obviating the necessity of providing the burner arm with the usual valve for controlling the flow of gas to the tip. 100

It will, of course, be understood that when the gas pressure is normal and it is desired to ignite the gas at the tip and the valve is in a position to prevent the gas from gaining access to the burner arm, the latch bar 105 27 may be manually released from the notch 24 at which time the valve will automatically move to the position shown in Fig. 2 in the drawing, thus establishing communication between the gas main and burner tip. 110

From the foregoing description, taken in connection with the accompanying drawing, it is at once apparent that a valve for gas mains has been provided which is simple in construction, inexpensive of manufacture, 115 yet highly efficient in use.

Having thus described the invention, what is claimed as new, is:

In a device of the class described, a casing, a cap at one end of said casing, having a central opening therein, a valve in said casing movable under pressure having a stem extending exteriorly of said casing through said opening, a spring controlled bar pivotally connected with said cap engageable with said stem to lock the valve. 120 125

against movement under pressure, and an extension on the top of said cap arranged concentrically of said opening having a slot therein through which said bar is passed whereby undue strain is prevented from being imposed on the pivotal connection between the bar and cap when said bar is engaged with said stem, and a receptacle mounted on the outer end of the stem and adapted to engage said extension. 10
In testimony whereof we affix our signatures.

JAMESON M. BURROWS.
HENRY F. TRENARY.
